UNITED STATES PATENT OFFICE.

JOHN SCHIES, OF ANDERSON, INDIANA.

APPARATUS FOR MANUFACTURING GLASSWARE.

1,027,567.

Specification of Letters Patent.

Patented May 28, 1912.

Application filed May 5, 1909. Serial No. 494,128.

To all whom it may concern:

Be it known that I, JOHN SCHIES, a citizen of the United States, residing at Anderson, in the county of Madison and State of Indiana, have invented certain new and useful Improvements in Apparatus for Manufacturing Glassware, of which the following is a specification:

My invention relates to apparatus for manufacturing glassware in which the glass is subjected to pressure, and especially to apparatus of the character adapted for making hollow glassware, such as jars, bottles or the like, and in which the glass-blank is first subjected to pressure for forming a plastic pressed hollow blank which is then subjected to a blowing operation, and I have exemplified my invention in a machine of the latter character, indicating only such parts of the machine, however, as are necessary to illustrate my invention.

It has been a practice heretofore in machines of the latter character to employ a presser-plate on the plunger-head which is held by spring-pressure upon a usual neck-mold while the plunger is being released from the pressed blank, the presser-plate upon such release following the plunger in its upward movement. A mechanism of this character is illustrated in Letters Patent No. 722,634, granted me March 10, 1903, for glass blowing machine. Machines of this character have been used in which a multiple of springs have been employed to exert pressure upon the presser-plate, sometimes two, at other times three or four, or any number that might be desired. One of the objections to mechanism of this character has been the difficulty of maintaining the springs of a given plunger-head at equal elastic strength, resulting in different pressures at different points of the presser-plate. Another objection has been the annoyance occasioned by the breaking of the springs and the difficulty of finding springs having elastic strength similar to those already upon the head, and the loss of time occasioned by changing springs, these difficulties being enhanced by the fact that in operation the springs are subjected to heat and are liable to lose elasticity or strength in consequence.

It is the object of my invention to avoid these difficulties and to provide a device that will dispense with the necessity of using

springs for the purpose mentioned, and to provide a device in which the pressure upon the presser-part may be maintained uniform throughout the presser-part.

It is a further object of my invention to provide a press-mold and a plunger, with operating means for causing approach between the same, and an elastic-fluid cushioning means operatively disposed between the press-mold and plunger; further to provide a press-mold and a plunger, with operating means for causing reciprocation between the same, and a presser-part, there being relative movement between said plunger and presser-part, and elastic-fluid cushioning means for said last-named movement; and, further, to provide means for regulating the cushioning effect of said cushioning means.

My invention will be further readily understood from the following description and claims, and from the drawings, in which latter:

Figure 1 represents a side elevation of so much of a machine for making hollow glassware as is necessary to illustrate the application of my invention and embodying an exemplification of my invention, the same being partly broken away for better illustration of parts, and the plunger being in raised position. Fig. 2 is a plan view of the same, partly broken away. Fig. 3 is an enlarged side elevation of the same, partly broken away for better illustration of parts, but showing the plunger in depressed position. Fig. 4 is a detail of the cushioning means, in section on the line $z-z$ of Fig. 1.

I have illustrated my invention as applied in a machine which embodies a press-mold table and a blow-mold table.

1 represents a press-mold table which is journaled about a column 2, the table having thereon a suitable number of press-molds, one of which is shown at 3. The press-molds are arranged to be alternately positioned under a plunger 4 in usual manner.

5 indicates a blow-mold table adapted to rotate in unison with the table 1 and arranged to have thereon a suitable number of blow-molds, the tables being intermittently rotated in suitable or ordinary manner.

Reciprocating movement is provided between the press-mold and the plunger. I have shown this accomplished by means of a

rod 6 which acts on the plunger for reciprocating the same, the rod having connection with a piston 7 operating in a cylinder 8 in usual manner. This operation may be accomplished by compressed air received through a feed-pipe 9 and through pipes 10 11 connecting with the interior of the cylinder 8 at the respective sides of its piston, a controlling valve 12 for the same being 10 provided, which is manipulated by an operating-lever 13.

14 represents a suitable mold, shown as a separable neck-mold of usual construction, which is arranged to be placed upon the 15 press-mold 3, and is provided with suitable suspending means for the pressed glass-blank, shown at 15, these suspending means being for instance the threads 16 at the neck-end of the fruit-jar.

17 is a presser-plate which may have a presser-ring 18 suitably secured thereto and arranged to contact the neck-mold upon descent of the plunger for confining the molten glass which has been introduced into 25 the press-mold; the shank of the plunger fitting the central aperture of said presser-ring.

There is an elastic-fluid cushioning device interposed between the operating rod 30 6 and the press-mold which comprises a cylinder 19 and a piston 20 therefor, one of said parts being connected with the plunger and the other with the presser-plate. Thus the plunger 4 is suitably secured to 35 the cushion-cylinder 19 as by being fastened to a flange 21 thereon by means of bolts 22. The plunger may be provided with a cavity 23 which is coincident in position with a cavity 24 in the cylinder 19 and has an inlet-pipe 25 and an outlet-pipe 26 communicating with said cavity for the purpose of providing circulation of a cooling agency in said cavity, for instance water, in order 40 to maintain the plunger at proper temperature for acting upon the molten glass.

The cushion-piston 20 is shown as provided with expansion-rings 20' and connects with the presser-plate 17 in suitable manner, as by means of rods 27 preferably 50 rigidly secured to the piston and to the presser-plate, the presser-plate being preferably prevented from turning as by passing said rods through bearings 28 in lugs 29 of the cylinder 19. The cylinder 19 is prevented from turning by a rod 30 secured to 55 said cylinder and slidably in a bearing 31 on the operating cylinder 8.

32 is a lift-out for lifting the pressed blank out of the press-mold and may be of 60 usual construction. I have shown the same as comprising a yoke 33 on which trips 34 are pivoted on bolts 35, the trips being arranged to be received under lugs 36 at the respective sides of the neck-mold. The 65 yoke is secured to a piston-rod 37 having

a piston 38 attached thereto which reciprocates in a cylinder 39, a branch-pipe 40 connecting the pipe 10 with one end of the cylinder 39 and a branch-pipe 41 connecting the pipe 11 with the other end of said cylinder, a rod 42 secured to the yoke and sliding in a bearing 43 preventing said yoke from turning. Movement of the operating lever 13 in one direction will cause descent of the plunger and lift-out, and movement 70 of said operating lever in the other direction will cause ascent of said plunger followed by ascent of said lift-out, as more fully shown and described in Letters Patent Nos. 855,344 and 855,345, granted me May 80 28, 1907.

A suitable blank of molten glass is received in the press-mold in usual manner, the neck-mold being placed on the press-mold, when by manipulation of the operating lever 13, the controlling valve 12 is turned for admitting compressed air above the piston 7, whereby the cushion-cylinder 19 and piston 20 are caused to approach the press-mold. When the presser-ring 18 engages the neck-mold, the presser-plate will be arrested, causing arrest of the cushion-piston 20 and the compression of the air in the cylinder 19, this pressure being greatest at the lowermost limit of movement of 95 the plunger 4, and definitely positioning the presser-parts upon the neck-mold and acting as a firm clamp for the same, the plunger 4 passing through the presser-plate into the blank of molten glass for shaping the 100 same. The presser-ring confines the molten glass within the press-mold and the elastic-fluid compressed within the cushion-cylinder aids in recession of the plunger as soon as the operative force which moves the plunger 105 into the press-mold is released. The elastic-fluid cushion, which is at greatest compression just prior to recession of the plunger, acts on the neck-mold with a quick or kicking movement, aided by the weight 110 of the piston and presser-parts for causing clean release between the pressed glass blank and the plunger, the plunger continuing its ascent. An inlet-valve 44 permits the inlet of air into the cushion space for 115 permitting the piston to descend to its normal lowermost position against the shoulder 19', but this descent may be regulated by said valve for causing a prompt or retarded descent of said cushion-piston. As 120 shown, the valve 44 comprises a valve-seat 45 in the cylinder, a valve-proper 46 on a stem 47 passing through a cup 48 secured to the head 49 on the cylinder 19, the stem having a spring 50 thereabout, the tension 125 of which may be regulated by a nut 51, air-passages 52 being provided in said cup and communicating with the interior of the cylinder 19.

Pressure-regulating means are provided 130

for said elastic-fluid cushioning means. Thus 53 is an auxiliary cylinder which communicates with the main cushion-cylinder 19 as by means of a passage 54 and a pipe 55 threaded in an opening 56 in the head of the cushion-cylinder, which communicates with the interior of said cushion-cylinder, the said pipe 55 being secured to the auxiliary cylinder in suitable manner and communicating with the interior thereof. 57 10 is a piston for the auxiliary cylinder arranged to be positioned therein for increasing or decreasing the cushion-space upon which the main cushion-piston acts. It is shown as provided with expansion-rings 15 57'. The positioning of this piston may be accomplished by means of a screw 58 having threaded bearing 59 in the end 60 of said auxiliary cylinder and operated by a hand-wheel 61, and so arranged that the turning 20 of the screw will regulate the position of the piston in the auxiliary cushion cylinder. 62' is a vent to rear of the piston 57.

The position of the piston in the auxiliary cushion-cylinder regulates the cubic space upon which the piston in the main cushion-cylinder acts at each operation of the plunger, whereby the amount of fluid, for instance air, which is acted upon by each compressing movement of the piston in the main cushion-cylinder, is determined, and thereby regulating the pressure exerted upon the presser-plate, and regulating this pressure in delicate manner. For further regulation 35 of this pressure I provide a relief-valve 62 so arranged as to operate upon the presence of a given pressure in the cushion-cylinder, means being provided for regulating this pressure. This relief-valve comprises a 40 valve-seat 64 with which a valve-proper 65 makes contact, the said valve having a stem 66 about which a spring 67 is coiled, the spring being located between the valve-proper and a nut 68 having threaded connection 69 with the valve-casing 70 for regulating the tension of the spring, the casing being provided with openings 71 through which the exhaust from the relief-valve may 45 pass. Assuming that the relief-valve is set for resisting a given pressure, when that pressure is exceeded in the cushion-space, the relief-valve will open for relieving the excessive pressure and immediately close for maintaining the balance of the pressure in 50 the cushion-space.

By means of my improved device, the pressure upon the presser-plate may be regulated to a nicety and a cushion provided for the presser-parts which will maintain the 60 mold and pressed glass blank in position while the plunger is passing through its initial movement of withdrawal from the pressed blank, this cushion acting between the plunger and the presser-plate for aiding 65 in withdrawing the plunger and holding the

presser-plate in position, the action being quick and in the nature of a kicking motion, for providing cushioned release of the plunger which will prevent injury to the pressed blank and insure proper withdrawal of the plunger and maintenance of position of the pressed glass-blank during such withdrawal. 70 Upon complete withdrawal of the plunger the pressed blank is lifted from the press-mold in usual manner and transferred to 75 the blow-mold, or other suitable mechanism provided for further operation upon the pressed blank.

My improved device insures equal pressure upon all parts of the presser-parts and permits delicate regulation of the pressure exerted upon the same. It is further substantial and avoids the necessity of frequent renewing of parts.

Having thus fully described my invention, 85 what I claim as new and desire to secure by Letters Patent is:

1. In an apparatus for manufacturing hollow glassware, the combination with a plunger, press-mold, and means for causing 90 approach between said plunger and press-mold, of elastic-fluid cushioning means operatively interposed between said plunger and press-mold and comprising two parts, namely, a piston and a cylinder having a 95 fluid-compression space between them, the compression of said fluid being caused by relative movement between said two parts, one of said parts having connection with said plunger and the other of said parts 100 having connection with said press-mold and both of said parts acted on by said means for causing approach between said plunger and press-mold for compressing the fluid in said cylinder, the said compressed fluid in 105 said compression-space urging quick recession between said plunger and the pressed glass in said press-mold upon the retraction of said last named means, for the purpose described. 110

2. In an apparatus for manufacturing hollow glassware, the combination with a plunger, a press-mold, means for causing approach between said plunger and press-mold, and a presser-part, there being relative movement permitted between said plunger and presser-part, of elastic-fluid cushioning means comprising two parts, namely, a piston and a cylinder having a fluid compression space therebetween, arranged for resisting said last-named movement and thereby compressing the elastic-fluid in said space, one of said parts having connection with said plunger and the other of said parts having connection with said presser-part and constructed and arranged for urging recession, by the action of the elastic-fluid compressed in said space, between said plunger and the glass pressed in said press-mold with an explosive impulse, upon re- 120 125 130

traction of said means for causing approach between said plunger and press-mold, substantially for the purpose described.

3. In an apparatus for manufacturing hollow glassware, the combination with a plunger, a press-mold, means for causing approach between said plunger and press-mold, and a presser-part, there being relative movement permitted between said plunger and presser-part, of elastic-fluid cushioning means comprising two parts, namely, a piston and a cylinder having a fluid-compression space therebetween, the compression of said fluid being caused by relative movement between said two parts, and arranged for resisting said last-named movement and thereby compressing the elastic-fluid in said space, one of said parts having connection with said plunger and the other 20 of said parts having connection with said presser-part and constructed and arranged for urging recession, by the action of the elastic-fluid compressed in said space, between said plunger and the glass pressed in 25 said press-mold, upon retraction of said means for causing approach between said plunger and press-mold, and means for adjusting the capacity of resistance of said elastic-fluid cushioning means, for the purpose described.

4. In an apparatus for manufacturing glassware, the combination with a plunger and press-mold, of a plunger-actuating piston and cylinder, and a fluid-compression 35 plunger-cushioning piston and cylinder arranged in alinement and in different cross-sectional planes, for the purpose specified.

5. In combination, in an apparatus for manufacturing glassware embracing a plunger and presser-part, an elastic-fluid cushioning device comprising a piston and cylinder operatively interposed between said plunger and presser-part and forming a single elastic-fluid cushion acting upon said 45 presser-part at a plurality of points, cross sectionally of the area of said presser-part substantially as described.

6. In combination, in an apparatus for manufacturing glassware embracing a plunger and presser-part, an elastic-fluid cushioning device comprising a piston and cylinder operatively interposed between said plunger and presser-part and forming a single elastic-fluid cushion acting upon said 55 presser-part at a plurality of points, cross sectionally of the area of said presser part and adjusting means for said cushioning means, substantially as described.

7. In combination, in an apparatus for manufacturing glassware, embracing a plunger, a press-mold, a presser-part, and operating means for causing reciprocation between said plunger and presser-part and said press-mold, of elastic fluid-cushioning 65 means between said plunger and presser-

part comprising two parts, namely, a piston and a cylinder having fluid-compression space therebetween, the fluid wherein is compressed by the advancing movement of said operating means, one of said parts having connection with said plunger and the other of said parts having connection with said presser-part, and constructed and arranged whereby an initial kicking retraction is imparted to said plunger by said compressed fluid upon retraction of said operating means, substantially as and for the purpose described.

8. In combination, in an apparatus for manufacturing glassware, embracing a plunger, a press-mold, a presser-part, and operating means for causing reciprocation between said plunger and presser-part and said press-mold, of elastic cushioning means acting on said plunger and said presser-part comprising two parts, namely, a piston and a cylinder having a fluid-compression space therebetween, the fluid wherein is compressed by the advancing movement of said operating means, one of said parts having connection with said plunger and the other of said parts having connection with said presser-part, and constructed and arranged whereby an initial kicking retraction is imparted to said plunger by said compressed fluid upon retraction of said operating means, and automatically acting pressure relieving means for said cylinder, substantially for the purpose described.

9. In combination, in an apparatus for manufacturing glassware, embracing a plunger, a press-mold, a presser-part, and operating means for causing reciprocation between said plunger and presser-part and said press-mold, of elastic fluid-cushioning means acting on said plunger and said presser-part and comprising two parts, namely, a piston and a cylinder having fluid-compression space therebetween, the fluid wherein is compressed by the advancing movement of said operating means, one of said parts having connection with said plunger and the other of said parts having connection with said presser-part, and constructed and arranged whereby an initial kicking retraction is imparted to said plunger by said compressed fluid upon retraction of said operating means, and a normally closed automatic relief-valve communicating with said fluid-compression space, substantially for the purpose described.

10. In combination, in an apparatus for manufacturing glassware, embracing a plunger, a press-mold, a presser-part, and operating means for causing reciprocation movement between said plunger and said presser-part and said press-mold, of elastic fluid-cushioning means acting on said plunger and said presser-part comprising two parts, namely, a piston and a cylinder having a

uid-compression space therebetween, the fluid wherein is compressed by the advancing movement of said operating means, one of said parts having connection with said plunger and the other of said parts having connection with said presser-part, and constructed and arranged whereby an initial kicking retraction is imparted to said plunger by said compressed fluid upon retraction of said operating means, an auxiliary cylinder communicating with the elastic fluid-space in said cylinder, and means for regulating the cushioning space in said auxiliary cylinder, substantially for the purpose described.

11. In combination, in an apparatus for manufacturing glassware, embracing a plunger, a press-mold, a presser-part, and operating means for causing reciprocation between the said plunger and presser-part, of elastic fluid-cushioning means acting on said plunger and said presser-part comprising two parts, namely, a piston and a cylinder having a fluid-compression space therebetween, the fluid wherein is compressed by the relative movement between said plunger and presser-part caused by the advancing movement of said operating means, one of said parts having connection with said plunger and the other of said parts having connection with said presser-part, and constructed and arranged whereby an initial kicking retraction is imparted to said plunger by said compressed fluid upon retraction of said operating means, an auxiliary cushion-cylinder, a normally closed relief-valve having communication with said cylinder, and means for adjusting the relieving effect of said auxiliary cushion-cylinder and relief-valve, substantially for the purpose described.

12. In an apparatus for manufacturing hollow glassware, the combination with a plunger and presser-part, of a piston and cylinder operatively interposed between said plunger and presser-part for forming elastic-fluid cushioning means between said plunger and presser-part, substantially as described.

13. In an apparatus for manufacturing glassware, the combination with a plunger and press-mold, of means for causing reciprocating movement between said plunger and press-mold, and an elastic-fluid cushioning device operatively interposed between said last-named means and said plunger and press-mold and acting for urging quick withdrawing movement between said plunger and press-mold, upon retraction of the first named means substantially for the purpose described.

14. In an apparatus for manufacturing hollow glassware, the combination with a plunger and press-mold, of means for causing reciprocating movement between said plunger and press-mold, and an elastic-fluid cushioning device operatively interposed between said last-named means and said plunger and press-mold and acting for urging quick withdrawing movement between said plunger and press-mold, upon retraction of said first named means said elastic-fluid cushioning device and plunger being disposed in alinement, substantially for the purpose described.

15. In an apparatus for manufacturing hollow glassware, the combination with a plunger and press-mold, of means for causing reciprocating movement between said plunger and press-mold, and an elastic-fluid cushioning device operatively interposed between said last-named means and said plunger and press-mold, and acting for urging quick withdrawing movement between said plunger and press-mold upon retraction of said first named means, said last-named means, plunger, press-mold and elastic-fluid cushioning device being in line with each other, substantially for the purpose described.

In testimony whereof, I have signed my name hereto in the presence of two subscribing witnesses.

JOHN SCHIES.
